A. PETERSEN

BOBBIN STAND FOR BRAIDING MACHINES

Filed Aug. 16, 1922

Inventor:
Anker Petersen
but Robert Cushman
Atlys.

UNITED STATES PATENT OFFICE.

ANKER PETERSEN, OF WINTHROP, MASSACHUSETTS.

BOBBIN STAND FOR BRAIDING MACHINES.

Application filed August 16, 1922. Serial No. 582,164.

To all whom it may concern:

Be it known that I, ANKER PETERSEN, a citizen of the United States of America, and resident of Winthrop, in the county of Suffolk and State of Massachusetts, have invented new and useful Improvements in Bobbin Stands for Braiding Machines, of which the following is a specification.

This invention concerns braiding machines of that type wherein two series of bobbins are caused to revolve in opposite directions about a common center and having means for causing the threads from the outer series of bobbins to pass alternately over and under successive bobbins of the other series, and relates more particularly to an improved stand or support for the bobbins of the outer series.

The object of the present invention is to simplify the construction of braiding machines of the above type by reducing the number of parts employed, thus decreasing the weight and air resistance of the revolving mass, and more specifically to provide an improved type of bobbin stand for supporting bobbins of the outer series, each stand having bearings for adjacent bobbin spindles so as to decrease by one-half the number of brackets usually employed.

In the drawings there is illustrated by way of example a preferred form of bobbin stand embodying the present invention and in such drawings,—

Fig. 1 is a fragmentary plan view of a braiding machine of the type above referred to, showing the device of the present invention applied thereto;

Fig. 2 is a fragmentary side elevation of the machine shown in Fig. 1;

Fig. 3 is an inside elevation of one of the bobbin stands forming the subject matter of the present invention;

Fig. 4 is a side elevation of such bobbin stand; and

Fig. 5 is a horizontal cross section on the line 5—5 of Fig. 3.

Referring to the drawings, the circular frame of a braiding machine is indicated at 1 while the numeral 2 designates the rotating support upon which the outer series of bobbins 3, 3^a etc. is mounted. A stationary support or track 4 is arranged concentric

with the support 2 and serves to guide and support the inner series of bobbin carriers 5, 5^a etc. provided with the bobbins or spools 6, 6^a respectively. The yarns or threads from these latter bobbins pass through suitable guides to the center of the machine for interbraiding with the threads or yarns from the outer series of bobbins or spools. The threads from the outer series pass through guide members 7 fixed to the support 2 and through guide eyes in movable detector fingers 8 and thence to the warp levers 9 by means of which they are caused alternately to pass above and below the bobbins of the inner series all in a manner well known in the art.

In accordance with the present invention, the bobbins or spools of the outer series are supported upon bobbin stands each of which comprises a base member 10 having openings 11 for the reception of screws or bolts by means of which the base member may be secured to the rotating support 2. A post 12 rises from the base member preferably having an inwardly extending and substantially radial rib 13. From opposite sides of this rib at the upper part of the post, flange members 14, 15 project, which serve to define outwardly inclined slots or pockets 16, 17 respectively, open at their upper ends and provided with flaring guide mouths 18, if desired. The lower ends of these slots terminate in curved walls 19, 20 respectively, constituting bearings for the ends of bobbin spindles as hereinafter described. As indicated in Figures 3 and 5, the bearings 19, 20 lie in substantially the same horizontal plane but have their axes disposed angularly with respect to each other.

A pair of lugs 21, 22 project outwardly from the outer edge of the base 10, being provided with bearing openings 23, 24 respectively, arranged in the same horizontal plane but having their axes substantially parallel respectively to the axes of the bearings 19, 20. A second pair of lugs 25, 26 project from the inner edge of the base 10, these lugs having bearing openings 27, 28 lying in the same horizontal plane but with their axes parallel respectively to the axes of the bearings 19, 20. A lug 29 projects from the central portion of the base in an

inward direction and has a bearing opening 3 whose axis is substantially parallel to that of the bearing 19. A screw threaded opening 31 intersects the bearing opening 30 substantially at right angles thereto.

As indicated in Figure 2, the adjacent ends 32, 33 of the spindles of neighboring bobbins 3, 3^a respectively are seated within the bearings 19, 20 formed by the lower ends 10 of the pockets 16, 17. The opposite ends of the spindles 32, 33 are similarly positioned in bearings formed in the next adjacent bobbin stands to the right and left of the post 12 respectively, it being understood that, 15 these bobbin stands are similar in all respects to that shown in Figs. 3 to 5. Adjacent ends of detector shafts 34, 34^a are journalled in the bearings 23, 24, the remote ends of these shafts being mounted in 20 similar journals in adjacent bobbin stands. These shafts have fixed thereto the detector fingers 8 above referred to and are constantly urged in one direction by means of coil springs such as 35. During the normal 25 operation of the machine, the tension of the yarn holds the fingers 8 outwardly and away from the support 2 in opposition to the springs 35 but when the yarn breaks the shafts 34, 34^a rotate under the action of the 30 springs 35 and complete an electrical circuit in well known manner for stopping the machine.

The bearings 27, 28 support adjacent ends 35 of exhaust detector shafts 35^a 35^b having 35 detector fingers 36, 36^a secured thereto. These shafts normally tend to rotate under the action of springs 37, 37^a respectively in such manner as to hold their detector fingers in contact with the yarn mass upon 40 the spools 3, 3^a etc. When the yarn mass is exhausted the detector fingers move inwardly, completing an electrical circuit in known manner for stopping the machine.

A shaft 38 is secured in the bearing opening 30 by means of a set screw 39, and this shaft supports a bobbin tension device 40 comprising a series of resilient fingers which bear against the outer surface of the thread mass to retard the rotation of the latter, 50 thus tensioning the yarn.

The bobbin stand herein described provides all the necessary bearings for adjacent ends of the spindles of neighboring bobbins, as well as the detector means associated therewith and each stand also provides means for supporting the bobbin tension device for one bobbin. By the employment of this bobbin stand, it is possible to dispense with one-half the number of stands 55 customarily employed, thus decreasing the weight and air resistance of the rotating parts while at the same time cutting down the cost of construction and giving the machine a more pleasing appearance.

While as herein disclosed the bobbin stand

is provided with supporting elements for the bobbins and certain associated parts, it is contemplated that some of these elements might be dispensed with under certain circumstances or that other and additional 70 supporting means might be provided if occasion should so demand.

What I claim and desire to secure by Letters Patent of the United States is:

1. A bobbin stand for braiding machines 75 of that type having a rotating support and a series of bobbins mounted thereon comprising a post constructed and arranged to be secured to said support, and bearings in said post for the spindles of adjacent bobbins of the series.

2. A bobbin stand for braiding machines comprising a base member, and a post upstanding therefrom, said post being provided with a pair of bearing openings disposed angularly with respect to each other, and constructed and arranged to receive the ends of a pair of adjacent bobbin spindles. 85

3. A bobbin stand for braiding machines comprising a base member, and means providing a pair of open pockets disposed angularly with respect to each and constructed and arranged to form bearings for the spindles of adjacent bobbins. 90

4. A bobbin stand for braiding machines 95 comprising a post having a pair of downwardly inclined slots provided with curved bottom walls constituting bearings for the ends of adjacent bobbin spindles, the axes of said bearings lying substantially in the 100 same horizontal plane and intersecting each other at an angle.

5. A bobbin stand for braiding machines comprising a base member, a post rising 105 therefrom, said post having a centrally disposed longitudinal strengthening rib on one side, and a flange member projecting laterally from either side of said rib, each flange providing an upwardly open bearing pocket, the bottoms of which are in the same horizontal plane, said pockets constituting bearings for the reception of the ends of the 110 spindles of adjacent bobbins.

6. A bobbin stand for braiding machines 115 of that type having a rotating support and a series of bobbins mounted thereon and rotating therewith comprising a base member, a post rising from said base member and having a radial strengthening rib upon its inner side, and a pair of flanges projecting 120 from opposite sides of said rib adjacent to the top of the post, said flanges defining downwardly and outwardly inclined slots upwardly open and having curved bottom walls constituting bearings for the ends of 125 the spindles of adjacent bobbins of the series.

7. A bobbin stand for braiding machines comprising means constituting bearing openings for the spindles of adjacent bobbins. 130

bins, and means for supporting adjacent portions of thread break detectors for the respective bobbins.

8. A bobbin stand for braiding machines of that type having a series of bobbins comprising bearings for adjacent ends of the spindles of adjacent bobbins of the series, and supports for portions of the thread exhaust detecting means for adjacent bobbins.

10 9. A bobbin stand for braiding machines of that type having a series of bobbins comprising bearings for adjacent ends of the spindles of adjacent bobbins of the series, and means for supporting a thread tension

15 device for one of said bobbins.

10. A bobbin stand for braiding machines of that type having a rotating support and

a series of bobbins mounted thereon, comprising a base for attachment to said support, a post rising from the base, a pair of 20 bobbin spindle bearings carried by the post, a pair of yarn break detector bearings carried by the base, a pair of yarn exhaust detector bearings carried by the base, the bearings of said pairs being angularly disposed 25 with respect to each other and respectively cooperating with the adjacent ends of the spindles and detector devices of adjacent bobbins of the series, and means carried by the base for supporting a yarn tension device for one of said adjacent bobbins.

Signed by me at Boston, Massachusetts,
this ninth day of August, 1922.

ANKER PETERSEN.
